UNITED STATES PATENT OFFICE

OLAF C. OLSEN, OF DAYTON, OHIO, ASSIGNOR OF TWO-THIRDS TO THE BORDEN COMPANY, OF WARREN, OHIO, A CORPORATION OF OHIO

REFRIGERATING APPARATUS

Application filed August 30, 1927. Serial No. 216,392.

This invention relates to improvements in refrigerating systems, and particularly to that part of a system which is designed to be placed within the refrigerator and which is referred to hereinafter as the refrigerating unit.

One of the objects of the invention is the provision of a refrigerating unit having a control mechanism which shall be readily accessible.

Another object of the invention is the location of the control mechanism upon a removable end wall of the float chamber, said end wall being located parallel with and close to the front end of the freezing compartment, whereby it becomes accessible whenever the freezing compartment is made accessible, as by the opening of a door of the refrigerator.

Other objects, and objects relating to details of construction, will appear as I proceed with the description of that embodiment of the invention which, for the purposes of the present application, I have illustrated in the accompanying drawings, in which:

25 Figure 1 is a front elevational view of a refrigerating unit embodying my control mechanism.

Figure 2 is a side elevational view of the same.

30 Figure 3 is a cross sectional view on a larger scale of the cover plate of the float chamber and certain associated parts, the view being taken substantially on the line 3—3 of Figure 1.

Figure 4 is a detail vertical sectional view of one of the connectors for the system, and

Figure 5 is a diagrammatic illustration of a refrigerating system embodying my invention.

40 Similar reference characters refer to like parts throughout the views.

Referring first to Figure 5 of the drawings, the refrigerating system there shown embodies a compressor pump 10 adapted to receive 45 expanded gas through pipe 11, to compress it and to deliver it through pipe 12 into a condensing coil 13. The lower end of condensing coil 13 empties into a liquid receiver 14, from which a pipe 15 containing a hand valve 15' 50 leads back to the control mechanism, gen-

erally designated 16. From the latter liquid refrigerant under low pressure flows through a coil of pipe 17, constituting the evaporating coil within which are arranged the freezing trays 18, while the gas given off by evaporation flows from the opposite end of the coil 17 into the float chamber of the control mechanism, as will more clearly appear herein-after.

The upper portions of the various loops of the coil 17 are clamped in position by a rod or bar 19 in the upper edge or edges of which are formed notches 20 to receive the pipe loops, together with a rod or bar 21 having curved extremities, the two bars 19 and 21 being secured together and clamped upon the loops of the coil 17 by means of machine screws 22. The bar 21 is of some little width and supports upon its upper surface legs 23, which are secured to the bar by flat headed screws 24.

The legs 23 are integral parts of a casing 25 containing a float chamber. The rear end of the coil 17 is connected to this casing by means of a nipple and clamp nut 26, 27, as shown in Figure 2. The casing 25 is cast with its front end open, and a closure plate 28 is provided therefor and removably secured thereto by stud bolts 29 which pass into threaded holes in bosses 30 on the casing. The closure plate 28 carries all of the control mechanism.

Somewhat below its center the cover plate 28 is provided with a threaded opening 31 for the reception of a connector plug 32 at 55 the upper end of the pipe 15 leading from the condenser coil 13. The plug 32 is provided centrally with a constricted passage 33 controlled by a needle valve 34 also mounted in the plug and urged away from its seat in the passage 33 by a coil spring 35, bearing on the head of the valve which is of a size to fit a flanged cap 34' that is slideable in a guide hole 36 of the plate 28. The guide hole 36 extends through the plate into 60 a cavity 37 formed in the rear side thereof. The clearance between the head of the valve 34 and the wall of the guide opening 36 affords some connection between the cavity 37 and the valve, but I prefer to provide a 65

further unobstructed passage 38. The head of the valve is pressed by the spring 35 against a diaphragm 39, which forms the rear wall of the cavity 37, being clamped at its periphery against an annular shoulder 40 by a rib 42 on a circular plate 41 of considerably smaller diameter than the plate 28 and secured thereto by suitable means, as by screws 43.

10 The diaphragm 39 is movable outwardly by a stem 44, provided with a large head 45, and at its rear end with a bifurcation 46 which straddles a pin 47 mounted in a bifurcated lever 48 which is pivoted at 49 in brackets 50

15 on the plate 41. The upper end of the lever 48 is pivotally connected at 51 with a short link 52 which is in turn pivoted at 53 to the short arm of a bell crank lever 54 mounted at 55 on a pivot carried by a second pair of brackets 56 on the plate 41. The rear end of 20 the bell crank 54 is formed like a bail and is attached to a metal float 57.

Leading from the cavity 37 there is a passage 58 extending into a socket 59 in the 25 forward side of the plate 28. The socket 59 registers with a short transverse passage 60 in a special connector member 61 which I find it desirable to employ, although a simpler connector would serve the purpose.

30 The connector 61 has a pair of integral attaching lugs 62 through which securing studs 63 extend into threaded openings 64. The passage 60 connects with a cavity 65 and thence an axial passage 66 with the intake 35 end of the coil of pipe 17. The upper end of the passage 66 is adapted to be closed by a valve piece 67, on the end of a valve stem 68 which is threaded for up and down adjustment in the connector member, the smooth

40 portion of the stem running through a packing 69 which is held in place by a gland 70. The upper end of the stem 68 is squared, as shown at 71, for the reception of an operating wrench. When the valve piece 67 is 45 threaded upwardly to the limit of its movement its conoidal upper surface closes off the annular passage 72 which communicates by means of a plurality of radial passages 73 with an outer annular passage 74 that connects with a threaded socket 75 normally closed by a plug 76.

Above the maximum liquid level in the 50 float chamber an opening 77 extends through the cover plate 28, and has mounted therein 55 a connector 78 to which the pipe 11 is attached for conducting expanded gaseous refrigerant back to the compressor 10.

Operation

60 When the apparatus is assembled and it is desired to introduce refrigerant, the plug 76 in the special connector 61 is removed and a connection made between the refrigerant supply apparatus and the threaded socket 75. Charging of the apparatus then

proceeds, and when it is completed the valve stem 68 is threaded upwardly until the passage 72 is closed by the valve piece 67, when the connection from the refrigerant supply may be broken and the plug 76 replaced.

70 Now with the valve piece 67 in its upper position free flow of refrigerant is permitted from passage 60 to passage 66, and thence to coil 17. When in the course of the operation of the apparatus it becomes necessary to replenish the supply of refrigerant, the same procedure may be followed, except that the valve 67 must be caused to close the passage 72 before the plug 76 is removed.

75 Gaseous refrigerant is condensed in the coil 13, due to pressure exerted by the compressor 10, and flows as liquid under heavy pressure up to the constructed passage 33 in plug 32. Assuming that the valve 34 is not

tightly seated at the time, liquid moves in 80 small quantities past the valve into the cavity 37 and through passage 58 and socket 59 into passage 60 of the connector 61 and thence through cavity 65 and passage 66 into coil 17.

85 After passing the expansion valve 34 the pressure of the liquid is much reduced. While circulating through the coil 17, more or less of the liquid refrigerant is converted into a gas, thus absorbing heat, and this gas flows into the float chamber in 90 casing 25 through connector 27, after which it is drawn off through connector 78 and pipe 11 back to the compressor 10. When the level in the float chamber is sufficiently 95 high, the float 57 tilts the bell crank 54 on its pivot 55, actuating link 52 and lever 48 to cause pin 47 to move the stem to the left, as viewed in Figure 2, and to move valve 34 to closed position through the intermediacy of diaphragm 39. When the liquid 100 level descends, due to evaporation, the stem 44 is retracted somewhat and the spring 35 then acts to move the valve 34 to the right slightly and the flow of liquid into coil 17 is resumed and continued until the float 57 again rises sufficiently to close the expansion 105 valve 34. The coil 17 is, therefore, flooded at all times.

110 The refrigerating unit of this apparatus is so designed that all of the working parts are located upon the plate 28, and this is positioned in the front of the unit so that 115 repairs or replacements may be made with a minimum of labor and expense. The expansion valve, which is perhaps the element 120 requiring the greatest amount of servicing may be removed, inspected and repaired without the removal of the plate 28. When this is to be done the hand valve 15' is closed and the stem 68 is screwed down until the 125 valve piece 67 closes the passage 66. The pipe 15 may then be disconnected from plug 32 and the latter unscrewed and removed with the loss of but a small part of the refrigerant in the system.

Having thus described my invention what I claim as new is:

1. In a refrigerating system, an evaporator, control mechanism comprising a casing open at one end, said casing having a connection with the delivery end only of said evaporator, a closure for the open end of said casing, an expansion valve for controlling the intake end of said evaporator mounted outside of said casing, a float in said casing, said closure having an opening therethrough, a diaphragm sealing said opening, and operative connections between said float and diaphragm within the casing and between said diaphragm and valve outside of the casing for controlling the operation of said valve.

2. In a refrigerating system, an evaporator, a freezing compartment within said evaporator accessible from the front end thereof, controlling mechanism mounted outside of said evaporator near the front end thereof and directly adjacent thereto, said mechanism comprising a casing open at its front end, said casing having a connection with the delivery end only of said evaporator, a closure for said casing, an expansion valve adapted to admit refrigerant to the intake end of said evaporator, a float in said casing, said closure having an opening therethrough, a diaphragm sealing said opening, and operative connections between said float and diaphragm within the casing and between said diaphragm and valve outside of the casing for controlling the operation of said valve.

3. In a refrigerating system, embodying means for circulating refrigerant, a casing comprising a float chamber for the reception of refrigerant, a float in said chamber, a closure for one end of said chamber, a diaphragm in said closure, an expansion valve mounted upon said closure outside of said diaphragm, and operative connections mounted on said closure for actuating said valve from said float through the intermediary of said diaphragm.

In testimony whereof, I hereunto affix my signature.

OLAF C. OLSEN.
